UNITED STATES PATENT OFFICE.

NORMAN JONES AND STANLEY JONES, OF BOLTON, ENGLAND.

DETACHING ROLLER OF COMBING MACHINES FOR COMBING COTTON AND OTHER FIBROUS MATERIALS.

Application filed November 2, 1926, Serial No. 145,763, and in Great Britain November 13, 1925.

Our invention relates to combing machines for combing cotton or other fibrous materials and has reference to improved means for clearing the detaching rollers from fibers so that same are kept clean automatically by the improved mechanism to be set forth.

It is known to use a hinged board with flannel covered face to bear on the detaching rollers such board being turned-up for cleaning from time to time, and it is also known to use a rotatable flannel covered clearer roll, but these devices are not very effective with result that slubs or matted fiber is apt to fall down and become incorporated in the combed material, producing faults and interfering with the quality of the ultimate yarn.

As the combing machine is the last cleaning apparatus in the range of preparation machinery for cotton it is important the combed material pass forward free from all slubs or objectionable accumulations of flat waste, as such cannot afterwards be eliminated. Such results are not however obtainable with known clearing means.

We use a flannel covered revolving clearer roll which is driven frictionally and according to our invention we periodically and automatically clear the same by using a revolving stripping and storage fillet covered roller which is positively and automatically driven so as to effectively strip the revolving clearer so that a clean surface is always coming into action and the stripped material is stored until an opportune time for its removal.

The accompanying drawing illustrates our improvements and is referred to in the following detailed description. Only so much of the comber mechanism is illustrated as will enable our idea to be properly understood.

In such drawing:

Fig. 1 is a side elevation from the left-hand end of the comber head the view showing the revolving stripping and storage fillet covered roller and its actuating gear.

Fig. 2 shows a front view of the mechanism with the rollers broken in length.

Fig. 3 is an end elevation from the right-hand end of the comber head and shows the gear which actuates the flannel covered revolving clearer roll.

We use a revolvable flannel or similar

covered roll *a* which constitutes the revolving clearer. This roll *a* is preferably made from steel tubing and is truly cylindrical. It has trunnion ends *a'*, *a''* and is located between the front and back leather covered detaching rollers and is driven by friction from the back detaching roller *b*, which is shown, and this in the known way. The trunnions of the clearer roll *a* are carried in bearings in small brackets such as those marked *c*, *c'* from the cranked arms *d*, *d'* which embrace the known fulcrum or rocking shaft *e*. The slots *c*² and studs *c*³ provide for adjustment of the brackets *c*, *c'* and consequently of the revolving clearer *a*. As it is very important such revolving clearer *a* should not slip or fall back, as this is apt to cause any fiber collected thereon to become detached and fall into the combed material, we use a geared ratchet mechanism whereby any fractional advance of the revolving clearer *a* once made is assured. As an example, we show a small pinion *f* on the end of the axle *a'* which gears into a larger pinion *g* on a stud axle *g'*, this larger pinion *g* having combined with it a finely cut ratchet wheel *h* with which a pawl *h'* pivoted at *h*² engages. The pivot *h*² of the pawl *h'* is fixed in the bracket *c*. The stop marked *h*³ is to prevent the pawl *h'* jumping too high and failing to come into gear. The combination represents a suitable geared ratchet group but any other delicate non-return mechanism may be used which so acts that any fractional rotation of the revolving clearer *a* once made is assured. The letter *w* denotes the known weight hooks.

In connection with and mounted above the flannel covered revolving clearer roll *a* which contacts with and is driven by the back detaching roller *b* we mount a revolving stripping and storage fillet covered roller *i*. This has an axle *i'* the extremities of which fit into slots in the brackets *j*, *j'* which are bolted to the inside faces of the cranked arms *d*, *d'*. These brackets are adjustable being held by studs applied at *j*², *j*³. The brackets are slotted at *j*⁴ and the screws *j*⁵ permit of ready setting. The revolving stripping and storage fillet covered roller *i* acts as a stripper or cleaning roller to the flannel covered revolving clearer *a* and as a storage cylinder for the material removed, the fiber taken from the flannel covered re-

volving clearer roll being embedded in the dents on the roller *i* and thereby retained until the attendant strips the said roller *i*.

We arrange to slowly drive the revolving 5 stripping and storage fillet covered roller *i* in any convenient way. For example, we may fix a ratchet wheel *k* on the axle *i'* and actuate this from a slotted lever *l* loose on the axle *i'* said lever *l* having a pawl *l'* 10 pivoted at *l* with check stop *l*². Such slotted lever *l* could be worked by a pin or stud *m'* adjustably mounted on a bracket *m* secured to the pedestal of the front detaching rollers or otherwise.

15 The actuation of the flannel covered revolving clearer roll *a* and the revolving stripping and storage fillet covered roller is preferably so arranged that the former is nearing cessation of its rotation when the 20 latter is making its effective movement to perform the stripping or cleaning.

The entire combination is so constructed, mounted, and actuated to effectively deal with the back top detaching roller *b* but it 25 also clears the front detaching roller (not shown) as those conversant with the action of the Nasmith or like comber will understand, and, if the mechanism be watched at work, it will be seen the detaching rollers 30 are kept quite clear of fibers and that the revolving stripping and storage fillet covered roller keeps the flannel covered revolving clearer roll clean all the time, and slubs and flat waste cannot become detached. 35 The result is, a great decrease in faults in the combed material and by reason of the need for less attention an increase in production takes place. The revolving stripping and storage fillet covered roller is easily cleaned or stripped from time to time by a wire brush, because just as the waste easily embeds and becomes compacted in the overhanging teeth so the waste fibers are easily plucked out by a wire brush operated to 40 lift the fiber out. It is seen that the revolving stripping and storage fillet covered

50 roller *i* can be easily detached for cleaning, &c. by release of the pin *m'* which leaves the roller at liberty to be lifted out of its slotted bearings. Access is also easily had for the varnishing of the leather covered detaching rollers.

We may weight the front detaching roller by hooks with suspended bar engaging the two hooks and by a weight hung on the suspended bar. 55

The dents on the roller *i* may be variously arranged and it may be found that a revolving brush would serve as the cleaning and storage element such being obviously only 60 an equivalent to what we have described and shown.

We declare that what we claim is:

1. In connection with the detaching rollers of combing machines, the employment of 65 a revolving stripping clothed roller co-operating with a revolving clearer roll, and means to positively and automatically actuate the revolving stripping clothed roller to strip the revolving clearer roll, the waste 70 being stored on the revolving stripping clothed roller.

2. In connection with the detaching rollers of combing machines, the combination of 75 a driven revolvable stripping roller having a brush-like covering, a revolving clearer roll, and automatic driving means for ensuring fractional rotation in one direction of the revolvable stripping roller.

3. In combing machines and in connection 80 with the detaching rollers thereof, a revolving stripping roller, a fillet clothing thereon, a revolving clearer roll to which the revolving stripping roller works, and geared means for ensuring fractional rotation in one direction only of the revolving stripping roller.

In testimony whereof we have signed our names to this specification.

NORMAN JONES.
STANLEY JONES.
